UNITED STATES PATENT OFFICE.

CHARLES FRANK SAMMET, OF DALTON, MASSACHUSETTS, ASSIGNOR TO CRANE & COMPANY, OF DALTON, MASSACHUSETTS, A PARTNERSHIP.

SAFETY PAPER AND METHOD OF FORMING THE SAME.

No Drawing.

Application filed October 31, 1921. Serial No. 511,810.

To all whom it may concern:

Be it known that I, CHARLES FRANK SAMMET, a citizen of the United States, residing at Dalton, in the county of Berkshire, 5 State of Massachusetts, have invented certain new and useful Improvements in Safety Paper and Methods of Forming the Same, of which the following is a description.

My invention relates to the making of 10 ordinary paper safe against tampering or erasure, whereby after writing or printing or other marks have been applied thereto, it will be impossible to erase any such markings without the fact becoming evident.

15 The invention also relates to the formation of a convenient article containing the safety ingredient in ready form for application to the finished paper.

As set forth in applications executed of 20 even date herewith (Ser. Nos. 511,808 and 511,809), I have discovered that substances of the benzidine group, that is, primary amines such as benzidine, toluidine and dianisidine; and diphenylamin; and various 25 derivatives thereof which have the benzidine nucleus and the primary amine radical therein, and diphenylamin when incorporated with paper impart to such paper the quality of being permanently stained by 30 chemical ink eradicator which generally include oxidizing agents having the property of producing this stain although other ingredients of the eradicator may have a somewhat similar effect.

35 I have described and claimed in said other applications the product produced by the application of these ingredients—that is, the safety paper and also the process of making the same with the proportions of 40 ingredients used.

As a further development of this line of invention, I have discovered that good results can be accomplished—that is, as to making the paper safe from change, that is 45 to say any writing or mark made upon such paper cannot be bleached out without giving an indication that an attempt to eradicate the writing or other mark thereon has been made, by forming the substances or 50 ingredient to be used for that purpose, such as benzidine, diphenylamin, or the insoluble

salts thereof, in stick form by molding, or by any suitable means preferably with the addition of a small amount of binding agent, such as starch paste, in sufficient 55 quantity to make the particles of the ingredients co-here in a solid mass.

I, therefore, intend in this application for patent to include not only the product—that is, paper made by applying to it when finished by rubbing or sprinkling, or in any other way, the ingredient to the external face of the paper, but also desire to claim as an article of manufacture the ingredient used for the purpose when molded or formed 65 into stick form convenient for the purpose.

When it is desired to make any paper or document safe against chemical erasure all that is necessary to do is to rub said stick over either the whole surface of the paper 70 or document or that portion of it which it is most desired to make safe against chemical erasure, and then by blowing or dusting remove any surplus material adhering to the surface of the paper. Such 75 application of the stick may be made either before writing or printing or otherwise marking upon the surface of the paper, or thereafter, it being essential only that the surface of the paper have some of the material remaining thereon and that sufficient 80 remains thereon permanently to effect the desired purpose.

As heretofore stated, this stick may be composed of benzidine, or its homologues; 85 diphenylamin, or its homologues; or, instead of being in stick form, either of these ingredients may be sprinkled or dusted on and then rubbed in in any suitable manner.

By the expression "benzidine material" as used in the appended claims, I mean to include colorless primary amines such as benzidine, toluidine, dianisidine, etc., that is, substances which are closely related to benzidine when incorporated with paper, or the colorless salts thereof, such compounds having the double ring nucleus and primary amine groups therein.

Having thus described my invention, what 100 I claim as new and desire to secure by Letters Patent of the United States is:

1. Paper, having applied thereon an ingredient composed of colorless insoluble "benzidine material."
2. Paper, having applied thereon an ingredient composed of a salt of a member of the benzidine group.
3. Paper, having applied thereon an ingredient composed of an insoluble salt of a member of the benzidine group.
4. The process of making paper safe against chemical erasure which comprises the application to the surface thereof of a colorless insoluble benzidine material.
5. The process of making paper safe against chemical erasure which comprises the application to the surface thereof of a material including a salt of benzidine.
6. The process of making paper safe against chemical erasure which comprises the application to the surface thereof of a material including an insoluble salt of benzidine.

In testimony whereof, I affix my signature.

CHARLES FRANK SAMMET.
